CLAIM

The ornamental design for a display screen or portion thereof with graphical user interface for motor vehicle as shown and described.

DESCRIPTION

The FIGURE is a front view of a display screen or portion thereof with graphical user interface for motor vehicle, showing our new design.

The broken line showing of the display screen or portion thereof with graphical user interface for motor vehicle is for the purpose of illustrating portions of the display screen or portion thereof with graphical user interface for motor vehicle and forms no part of the claimed design.
